Specification for Design.

Patented Sept. 29, 1908.

Application filed July 22, 1908. Serial No. 444,874. Term of patent 7 years.

To all whom it may concern:

Be it known that I, CARL LEPPERT, a citizen of the United States, residing at Johnstown, in the county of Fulton and State of New York, have invented a new, original, and ornamental Design for Gloves, of which the following is a specification, reference being had to the accompanying drawing, forming part thereof.

The single figure of the drawings is a plan view of the back of a glove, showing my new design.

The design consists of rows of markings arranged side by side, extending longitudinally

of the glove and diverging toward the fingers and converging at their other ends. Each row is composed of small marks on the body part of the back of the glove, arranged in quincunx order substantially as shown in the drawings.

I claim:

The ornamental design for a glove, as shown and described.

CARL LEPPERT.
